H. G. Lorentz INVENTOR.

BY

Hans Liedholm ATTORNEY.

UNITED STATES PATENT OFFICE.

HERMANN G. LORENTZ, OF CROMWELL, CONNECTICUT, ASSIGNOR TO THE J. & E. STEVENS COMPANY, OF CROMWELL, CONNECTICUT, A CORPORATION OF CONNECTICUT.

TOY FIREARM.

1,348,285.

Specification of Letters Patent.

Patented Aug. 3, 1920.

Application filed April 27, 1920. Serial No. 376,902.

To all whom it may concern:

Be it known that I, HERMANN G. LORENTZ, a citizen of the United States, residing at Cromwell, in the county of Middlesex and State of Connecticut, have invented certain new and useful Improvements in Toy Firearms, of which the following is a specification.

This invention relates to toy fire arms. 10 The article may be any one of several different types. In that form of embodiment of the invention which I have selected for illustration in the drawings accompanying and forming part of the present specification, 15 the article is shown as a toy pistol. It might be a toy rifle or something of a like nature. This illustration I will set forth in detail in the following description so that those skilled in the art may practice the invention. 20 Obviously I am not restricted to the exact disclosure made by said drawings and description. I may depart therefrom in several respects within the scope of the invention defined by the claims following 25 said description.

It is the custom in the production of toy pistols, toy rifles and like pieces of ordnance made as play things, to have them of sectional form, the sections being cast and 30 united by screws or otherwise, the so-called action being supported by one of the sections. I provide a construction which is capable of quite inexpensive and ready manufacture. This novel construction comprises two sides or outer sections and an 35 intermediate section, all of them being of sheet metal. Owing to this fact the article can be more inexpensively and rapidly produced and assembled than where its parts 40 are cast. In the present case the two outer sheet metal sections and the intermediate action supporting section can be formed by suitable dies from sheet metal and they can be held in operative relation by rivets which 45 can be readily headed for the purpose.

Referring to said drawings:

Figure 1 is a side view of the fire arm with one of the side sections removed.

Fig. 2 is a cross section on the line 2—2 50 of Fig. 1.

Fig. 3 is a top plan.

Like characters refer to like parts throughout the several views.

As I have already observed, the toy fire arm may take any one of several forms. As 55 shown it is in the form of a toy pistol for exploding paper caps. It comprises two sides or lateral sections each denoted by 2 and virtually duplicates of each other. The two sections may be united in any one of 60 several different ways, rivets 3 being shown for the purpose, the rivets passing through registering perforations in the sides 2. It will be clear of course that these sides are 65 formed from sheet metal stock and they are practically the same in construction. Between the sides or sections 2 is clamped the action-supporting plate 4 this also being of sheet metal and being held substantially and securely between the sides or sections 2. 70 The action-supporting plate sustains the hammer 5 the operative portion of which is adapted to strike a paper cap placed upon the anvil 6 presented by mating portions on the sides or sections 2, the said sides or 75 sections having a slot for the passage and proper action of the hammer 5. Rigid with the hammer is the trigger 7.

The hammer 5 is mounted for swinging movement and it ordinarily but not essentially fits flatwise the action-supporting plate 4 which has a bearing 8 to receive a lug on the hammer 5 and thus provide for its necessary swing between its extreme positions. The operating spring for the hammer is designated by 9, its free end bearing 80 against the back of the hammer 5 fitting a notch therein, and its opposite end being supported by a bearing 10 which like the bearing 8 is struck or formed from the ac- 85 tion plate 4.

The various parts of the action are easily mounted upon the plate 4 and when they are thus plate with its parts as a unit will be positioned between the sides or sections 2 95 and the parts held in firm relation between the sections 2.

The action-supporting plate 4 closely fits between the sections 2 which obviously limits its motion. To aid further in securing 100 this result, said plate may have on its edges at proper places lugs or ears 11 which extend

through notches formed in the sections 2. The plate 4 may also have a lateral lug 12 which fits against the sections 2. One of the rivets 3, or the lower one, as shown, extends 5 through the plate 4. In view of these circumstances this plate 4 is substantially held against accidental movement.

What I claim is:

- 10 1. A toy fire arm comprising side sections each made up of a barrel part and a stock part integral with each other and stamped from sheet metal, an intermediate section between the side sections, rivets for uniting the side sections, one of the rivets extending 15 through the intermediate section, a hammer on said intermediate section, the latter having a bearing to receive the hammer, and also having a second bearing, and a spring engaging the second bearing and the hammer, both bearings being formed from the 20 intermediate section, the edge portions of the intermediate section engaging the side sec-

tions, the said intermediate section having lugs and the side sections being slotted to receive the lugs.

2. A toy fire arm comprising side sections each made of a barrel part and a stock part integral with each other and of sheet metal, an intermediate section between the side sections, having lugs, the side sections being slotted to receive the lugs to thus hold the intermediate section in place, a hammer supported by the intermediate section, a bearing for the hammer on the intermediate section, and a spring acting against the hammer, the intermediate section having a bearing for the spring.

In testimony whereof I affix my signature in the presence of two witnesses.

HERMANN G. LORENTZ.

Witnesses:

CHARLES B. FRISBLES,
ARTHUR A. AHLQUIST.
